UNITED STATES PATENT OFFICE.

HENRY C. BARNET, OF EASTON, PENNSYLVANIA.

FENCE.

SPECIFICATION forming part of Letters Patent No. 369,627, dated September 6, 1887.

Application filed November 8, 1886. Serial No. 218,275. (No model.)

To all whom it may concern:

Be it known that I, HENRY C. BARNET, of Easton, county of Northampton, and State of Pennsylvania, have invented certain new and 5 useful Improvements in Fences, of which the following is a specification.

My invention relates to that class of fences in which the individual rails are provided with means for locking or securing them in place in 10 the posts; and the object of my invention is to construct a fence which will be light, cheaply manufactured, and securely and firmly fastened together (without the use of nails or the like) in such manner that the individual rails cannot, after the fence is once put together, be removed or dislodged by animals or even persons passing through the fields which it may 15 inclose. To accomplish this end, I employ a slotted post and rails provided with locking 20 devices, arranged in the manner hereinafter more fully described, and which can best be explained and understood by reference to the accompanying drawings, in which—

Figure 1 is a side view of a section of the 25 fence. Fig. 2 is a top view of the same. Fig. 3 is a view of one of the intermediate posts. Fig. 4 is a vertical central section of the same. Fig. 5 is a perspective view of one of the rails or bars embodying my invention.

30 In the accompanying drawings, the binding-posts A A' are made of any ordinary construction and suitable material, (either wood, metal, or stone,) and are provided at their lower end with a plate or cross-piece, a, to prevent them 35 when placed in the ground from being withdrawn therefrom.

B B' B² are the intermediate posts, of usual construction, sharpened at their lower ends, so as to be readily driven into the ground. In 40 each post, at suitable intervals apart, are formed openings b, of any convenient size and proper configuration. I have shown them, however, in their preferred form—that is to say, substantially square or four-sided, slightly greater 45 in width than in height, as shown in the drawings.

The fence-rails C D E are made of plates or strips of iron or other material of substantially uniform width bent or turned up at the 50 ends to form lips c. I also form at one end of said rails, on the side opposite to the lip c, an enlargement or projection, d, preferably deeper

than the lip c, as seen in the drawings, which, when the rails are in position, serves in conjunction with the rails to fill the openings b 55 in the posts, and thereby prevent the rails from rattling or becoming loose.

F is a brace placed at each end of the fence, consisting of two parts, 1 2, having formed in them at suitable points openings 3 4 5, either 60 round or elongated, and secured together by bolt and nut, or otherwise, so as to permit the brace to be lengthened or shortened, as may be desired.

The lips e e, formed on brace F, are placed 65 against the binding or end posts and the next adjoining intermediate post, and held firmly in place by means of a nut and screw-threaded bolt or rod, f, which passes through the binding-post, one of the lips formed on brace F, 70 and the next intermediate post. In this way the binding-posts are effectually braced and held in upright position, and the distance between them remains unaltered and always the same. Care should be taken to see that the 75 openings in the posts are made of a size and shape to receive and snugly hold the end of the rail, as above described.

The fence is constructed by placing the binding-posts in the ground and driving the intermediate ones at any suitable distance apart. So This operation being completed, the end of one of the rails (say E) which does not have the projection or enlargement is inserted into the slot nearest the ground of the binding-post A, 85 and also passed through into the lowest opening in the next adjoining intermediate post, B. This act will bring the end of the rail having the projection or enlargement d into the lowest opening in the binding-post A. Then the 90 similar end of a second rail—for instance, rail D—is inserted into the lowest slot in the second post, B, and is carried through the lowest slot in the third post, B'. In so doing it will be seen that the end of the rail having the projection or enlargement is brought into the lowest opening in the second post, B, which, together with the rail C, already located therein, will fill the opening. The end of rail D, having the lip only, will enter the lowest opening 100 in the third post. The same operation is carried on rail by rail until all the openings are filled and the bars in position.

It will be noted that the lips clinch and em-

brace the posts on opposite sides, and thereby steady and firmly secure the same.

5 A fence constructed as above described may be put together with comparatively little labor and with great rapidity. The rails are securely locked in position and cannot be displaced or removed by animals or persons passing through the field inclosed.

Having described my invention, what I claim 10 is as follows:

1. A fence consisting of posts provided with suitable openings, and rails having formed upon one end a lip projecting at right angles, and upon the other end, and on the opposite 15 side, an enlargement or projection, substantially as described, and for the purposes set forth.

2. As a new article of manufacture, a fence-rail having formed upon one end a lip projecting at right angles, and upon the other end, and on the opposite side, an enlargement or 20 projection, substantially as described.

25 3. As a new article of manufacture, a fence-rail one end of which is provided with a lip, the other end being provided with a corresponding lip and an enlargement or projec-

tion on the side opposite to said lips, said lips and enlargement being formed at substantially right angles to said rail, as set forth.

4. A fence consisting of posts provided with suitable openings, and rails having formed upon one end a lip, the other end being provided with a corresponding lip and an enlargement formed on the side opposite to said lips, substantially as described. 30

35 5. A fence consisting of posts provided with suitable openings, and rails having formed upon one end a lip and upon the other a corresponding lip and an enlargement or projection, substantially as described, a brace adjustable lengthwise of the fence, and a rod passing through the end post and next adjoining post, these parts being arranged and operating substantially as described, and for the purposes set forth. 40

45 In testimony whereof I have hereunto set my hand this 3d day of November, 1886.

HENRY C. BARNET.
